UNITED STATES PATENT OFFICE

158,136

LADDER STEP

Harolde M. Simon, Utica, N. Y., assignor to Utica
Radiator Corporation, Utica, N. Y., a corpora-
tion of New York

Application May 16, 1949, Serial No. 2,681

Term of patent 14 years

(Cl. D15—8)

To all whom it may concern:

Be it known that I, Harolde M. Simon, a citizen of the United States, residing at Utica, county of Oneida, State of New York, have invented a new, original, and ornamental Design for Ladder Step, of which the following is a specification, reference being had to the accompanying drawing, forming a part thereof, wherein the figure is a perspective view of the ladder step, showing my new design.

I claim:

The ornamental design for a ladder step, as shown.

HAROLDE M. SIMON.
